UNITED STATES PATENT OFFICE.

JOHN HERMAN, OF NEW YORK, N. Y.

SUSPENDERS.

SPECIFICATION forming part of Letters Patent No. 231,798, dated August 31, 1880.

Application filed July 16, 1880. (No model.)

To all whom it may concern:

Be it known that I, JOHN HERMAN, of the city, county, and State of New York, have invented a new and Improved Suspender-Brace, 5 of which the following is a specification.

The object of my invention is to provide a new and improved suspender-brace formed of two shoulder-straps connected on the back by a transverse strap, each of the shoulder-straps 10 being attached at both ends to a separate hook-plate, upon which a ring or eye of a pulley or like device catches or takes, and through which pulley a cord terminating in three button-loops passes.

15 In the accompanying drawings, Figure 1 is a perspective view of my improved suspender-brace. Fig. 2 is a detail elevation of the hook and pulley.

20 Similar letters of reference indicate corresponding parts.

The rear end of the shoulder-strap A is passed through the slot B of the hook-plate C, and is then stitched so as to be rigidly attached to the said plate C, whereas the front end of 25 the strap A passes through the slot B' of the plate C, and is attached to a buckle, D, which embraces the strap, as shown. Both shoulder-straps A A are folded so as to pass outward, or form a break at E, and are connected by a 30 transverse strap or brace, F, which is attached to the straps A A at the folds E E.

The plate C is provided with a hook, G, from 35 which a pulley, H, or like device is supported. A cord terminating in three-button loops, K L M, is passed through each pulley H in such a manner that two of the loops, K L, are to its front, and the longer loop, M, to the rear of the pulley. The slots B and B' of the plate C are to be arranged at an angle to each other.

The device is used as follows: The arms are 40 passed through the large loops formed by the shoulder-straps A in such a manner that the brace F is on the back of the wearer. The front buttons, on each side of the belt of the pants, are to be passed through loops K L, and the 45 buttons at the rear end of the belt are to be passed through the loops M M, which must be crossed, as shown. If the pants are to be taken off, all that is necessary is to unhook the pulley H from the hooks G, for the entire 50 weight of the pants is supported by the said hooks.

The within-described suspender-brace supports the pants in a convenient and effective manner, without injuring the health of the 55 wearer or causing any pain, and permits of fastening or unfastening the pants very rapidly without requiring the suspenders to be unbuttoned.

Having thus described my invention, I 60 claim as new and desire to secure by Letters Patent—

1. In a suspender-brace, the combination, with the shoulder-straps A A, of the hook-plate C, pulley H, and the pants-supporting 65 cord terminating in three button-loops, K, L, and M, substantially as herein shown and described, and for the purpose set forth.

2. In a suspender-brace, the plate C, constructed, substantially as herein shown and described, with a hook, G, and the two slots B and B', at an angle to each other, as set forth. 70

JOHN HERMAN.
